United States Patent Office

Des. 204,866
Patented May 24, 1966

204,866

COVER FOR A PAPER ROLL HOLDER

Herbert G. H. Stewart, 1221 Franklin St.,
Santa Monica, Calif.

Filed Apr. 28, 1965, Ser. No. 85,009

Term of patent 3½ years

(Cl. D4—3)

FIG. 1.

FIG. 2.

FIG. 3.

FIG. 4.

FIG. 5.

The paper roll and fragmentary portion of a wall are shown in broken lines in FIGURE 1 for illustrative purposes only.

I claim:

The ornamental design for a cover for a paper roll holder, substantially as shown and described.
